UNITED STATES PATENT OFFICE.

MAX MOREY, OF BLISSFIELD, MICHIGAN.

DEVICE FOR BREAKING AND LOCKING RIMS.

1,168,097.

Specification of Letters Patent. Patented Jan. 11, 1916.

Application filed July 15, 1915. Serial No. 40,088.

To all whom it may concern:

Be it known that I, MAX MOREY, a citizen of the United States, residing at Blissfield, in the county of Lenawee and State of Michigan, have invented certain new and useful Improvements in Devices for Breaking and Locking Rims; and I do declare the following to be a full, clear, and exact description of the invention, such as will enable others skilled in the art to which it appertains to make and use the same.

This invention relates to new and useful improvements in tools for breaking the joint in clincher demountable rims when it is desired to remove the tire therefrom, and holding the same in open position while the tire is removed and replaced.

A further object of this invention is to provide a device which is simple and durable in construction, inexpensive to manufacture, and one which will be very efficient in operation.

With these and numerous other objects in view, the invention consists of certain novel features of construction, combination and arrangement of parts which will be herein referred to and more particularly pointed out in the specification and claims.

Figure 1 is a side elevation of the improved tool when the rim is broken; Fig. 2 is a side elevation with a portion of the operating lever broken away, showing the tool applied to a rim before the same is broken; Fig. 3 is a horizontal section taken on the line 3-3 of Fig. 2; and Fig. 4 is a central vertical transverse section taken on the line 4-4 of Fig. 2.

In describing my invention I shall refer to the accompanying drawings in which similar reference characters designate corresponding parts throughout the several views and in which the letter R indicates a portion of the ordinary type of rim, showing the same with the joint therein. The two ends of this rim are connected by the usual form of connection therebetween as shown at C.

Connected to the ends of the rim R adjacent the joint therein are a pair of clamps 1, which are adapted to project inwardly from the said rim. These clamps 1 are substantially alike, throughout their various parts, and I will describe one herewith. The clamp consists of two portions or sections 2 and 3 which have their lower surfaces conforming with the contour of the inner

surfaces of the rim R and have their lower ends thereof projecting under the sides of the same to prevent any upward movement therefrom. The upward inwardly projecting ends of the clamp sections 2 and 3 as shown at 4 are spaced a short distance from one another and are apertured as shown at 5 to receive a bolt 6 which is held thereon by a winged nut 7 on its outer end. This bolt is adapted to form a pivotal connection for the hinge members of this device as will be herein more particularly described.

The operating lever 8 has a curved handle 9 whose curvature conforms to the curvature of the inner surface of the rim R for a purpose which will be herein more particularly set forth. This lever 8 has a straight portion 9' which is bifurcated, and has a pair of alining apertures 10 extending therethrough adjacent its outer end.

A pair of link members 11 and 12 connect the lever 8 and the clamps 1. The links 11 and 12 are of unequal length, the longer link 11 being pivotally connected at one end 13 with one of the clamps, and has on its other end 14 a laterally extending offset portion which is pivotally connected as shown at 15 with the inner end of the bifurcated portion 9' of the operating lever 8.

The link 12 is shorter than the aforesaid described link 11 and is pivotally connected at one end to the remaining clamp 1 as has been herein described, and has its other end pivotally connected with the outer end of the bifurcated portion 9' of the lever 1 as shown at 16. The link 11 is provided with an aperture 17 intermediate its ends which is adapted to aline with the apertures 10 in the bifurcated portion 9' of the lever, when this device is in operative position. The clamps 1 which clamp the device to the rim are shown in this instance as adapted to be applied to a straight side demountable rim but they may be of any desired size or form to conform with the rim to which this device is to be applied.

In operation when the device is applied to the rim as shown in Fig. 2 of the drawings, and it is desired to part the rim at the joint of the same, the operating lever 8 is grasped at the curved handle 9 and swung to the position shown in Fig. 1 of the drawing. When in this position, it will be noted that the ends of the rim will be broken and positioned one above the other, and that also the curved portion 9 will be positioned

against the inner surface of a portion of the rim R, such positioning being made possible by reason of its curvature conforming to the curvature of the inner surface of said 5 rim.

The link members 11 and 12 which connect the lever 8 with the clamps 1 owing to the fact that they are pivotally connected with said lever between the sides of the 10 bifurcated portion of the same, will be positioned one above the other as clearly shown in Fig. 1 of the drawing. The offset at the end 14 of the link 11 when the device is in operative position, will position the pivotal 15 connection 15 between the said link and lever below the dead center of the line through the connection between the end of the link 12 and the lever and also the end 13 of the same and the clamp 1, which will thereby 20 tend to automatically lock this device in the above described position. This is obviously an improvement over other devices of this character which in the main depend upon an additional lever to accomplish the locking 25 operation which I accomplish as above described.

The above described automatic lock while sufficient for temporarily holding the same, for the ordinary purpose, will not hold 30 should any undue strain or stress be placed upon the rim R when held with its two ends broken, so I have provided an additional locking means for such use which consists of a pin 18 which projects through the alining 35 apertures 10 in the bifurcated end of the lever, and the aperture 17 in the link 11, which alines therewith when this device is in locked position to form an additional securing means which will be obvious. This 40 pin 18 is easily insertible through the said openings, and may be, if desired, secured thereto by any preferred form of securing means.

From the foregoing description of the construction of my improved device for breaking and locking rims, the manner of applying the same to use, and the operation thereof will be readily understood and it will be seen that I have provided a simple, inexpensive and efficient means for carrying out 50 the objects of the invention.

While I have particularly described the

elements best adapted to perform the functions set forth, it is obvious that various changes in form, proportion and in the 55 minor details of construction may be resorted to within the scope of the appended claims, without departing from the spirit or sacrificing any of the principles of this invention. 60

I claim:

1. A device of the character described comprising a pair of clamps for gripping the opposite ends of a rim adjacent the joint thereof, a lever with a bifurcated straight portion and a curved handle to correspond to the curvature of the inner surface of said rim, a short link connecting the outer end of said bifurcated portion and one of the clamps, and a long link pivotally connected 65 at one end to the remaining clamp and having a lateral projection on its other, pivotally connected with the inner end of said bifurcated portion, whereby said last mentioned pivotal connection may be positioned 70 below the dead center to lock the lever in operative position.

2. A device of the character described comprising a pair of clamps for gripping the opposite ends of a rim adjacent the joint 80 thereof, a lever with a bifurcated straight portion and a curved handle to correspond to the curvature of the inner surface of said rim, a short link connecting the outer end of said bifurcated portion and one of the 85 clamps, a long link pivotally connected at one end to the remaining clamp and having a lateral projection on its other pivotally connected with the inner end of said bifurcated portion, said link having an opening 90 therethrough intermediate its end alining with a pair of openings through the sides of said bifurcated portion adjacent the ends thereof when the lever is in operative position, and a pin projecting through said openings to pivotally lock the lever. 95

In testimony whereof I have hereunto set my hand in presence of two subscribing witnesses.

MAX MOREY.
